ELECTRIC WALL PLATE

Martin R. Lambertz, New Hamburg, Ontario, Canada,
assignor to Amerock Corporation, Rockford, Ill.

Original design application May 25, 1970, Ser. No. 23,119,
now Patent No. D. 223,746, granted June 6, 1972.
Divided and this application Aug. 2, 1971, Ser. No.
168,521

Term of patent 14 years

Int. Cl. D8—09

U.S. Cl. D8—181

FIG. 9.

FIG. 10.

FIG. 1 is a front view of an electric wall plate in the form of a switch plate incorporating my new design, the surface treatment being continued around the entire margin of the plate.

FIG. 2 is a fragmentary side view of the plate as seen from the right in FIG. 1.

FIG. 3 is a sectional view taken along the line 3—3 in FIG. 1.

FIG. 4 is an enlarged fragmentary sectional view taken along the line 4—4 in FIG. 1.

FIG. 5 is an enlarged fragmentary sectional view taken along the line 5—5 in FIG. 1.

FIG. 6 is an enlarged fragmentary sectional view taken along the line 6—6 in FIG. 1.

FIG. 7 is a front view of a modified form showing my design incorporated in a receptacle plate, the surface treatment being continued around the entire margin of the plate and the side view and sections being the same as shown in FIGS. 2, 4, 5 and 6.

FIG. 8 is a sectional view taken along the line 8—8 in FIG. 7.

FIG. 9 is a front view of a modified form of my design as embodied in a multiple switch plate with the surface

configuration being continued around the entire margin of the plate and the side view and sections being the same as shown in FIGS. 2, 4, 5 and 6.

FIG. 10 is a front view of a modified form of my design as embodied in a combined switch and receptacle plate with the surface configuration being continued around the entire margin of the plate and the side view and sections being the same as shown in FIGS. 2, 4, 5 and 6.

This application is a division of my copending application Ser. No. D. 23,119, filed May 25, 1970 now Pat. No. D. 223,746, granted June 6, 1972.

I claim:

The ornamental design for an electric wall plate, as shown and described.
